UNITED STATES PATENT OFFICE.

CLARENCE E. JEFFERS, OF INDIANAPOLIS, INDIANA, ASSIGNOR TO HOWARD C. MARMON, OF INDIANAPOLIS, INDIANA.

INSTRUMENT BOARD.

1,407,751.

Specification of Letters Patent. Patented Feb. 28, 1922.

Application filed November 17, 1919. Serial No. 338,650.

To all whom it may concern:

Be it known that I, CLARENCE E. JEFFERS, a citizen of the United States, residing at Indianapolis, in the county of Marion and 5 State of Indiana, have invented a new and useful Instrument Board, of which the following is a specification.

The object of my invention is to provide a compact instrument board for automobiles, 10 air ships, etc., so constructed that the instruments may be thoroughly illuminated, when desired, without any glare in the eyes of the operator, and without unnecessary illumination of parts other than the instruments to be observed.

The accompanying drawings illustrate my invention. Fig. 1 is a front elevation of a commercial embodiment of my invention for use on automobiles; Fig. 2 a rear elevation; 20 and Fig. 3 a section on line 3—3 of Fig. 1.

In the drawings, 10 indicates a rim-like main body of desired form conveniently chamfered around its outer edge to fit an opening in the board 11, and around its 25 inner edge to receive the glass plate 12.

Secured to the rear face of body 10 is an instrument-holding body 13 which also serves to retain glass 12 in its seat. Body 13 is conveniently provided with a number 30 of pockets 14 in which may be mounted desired instruments 15, held removably in place by appropriate fasteners 16 so that the instruments may, when necessary, be withdrawn from their pockets without removing 35 the entire structure.

Secured to, or formed integral with rim 10, preferably at its top, is a lamp-pocket 17, and mounted in body 13 is a lamp socket 18 preferably so arranged that the lamp 19 40 may be placed so as to overlie the upper edge of glass 12, the casing 20 thoroughly shielding the lamp so that no light rays may pass from it except by refraction through the glass. The filament of lamp 19 may 45 be conveniently arranged slightly to the rear of the inner face of glass 12 so that rays from the filament striking said face will be reflected to the faces of the instruments and by them reflected back through 50 the glass 12 to the observer.

By this arrangement, I find that the instruments are thoroughly illuminated by a very small power lamp and that there is no appreciable illumination of the space surrounding the driver, as is the case where the 55 source of light, even though shielded, is so arranged that rays may be reflected to the driver from the outer surface of the protecting glass.

With my arrangement, even the light rays 60 which strike the glass faces of the instruments and are reflected therefrom, must pass through glass 12 and there become so softened as to be unobjectionable.

I claim as my invention:

1. An instrument board, comprising a main body having a sight opening therethrough, an instrument having a face to be read through said opening, said instrument having greater dimensions than the sight 70 opening, means by which the instrument is held in place, a transparent cover carried by the main body and covering the face of the instrument, an electric lamp arranged with its filament substantially in the plane 75 of the transparent cover at an unobstructed edge thereof, and a shield preventing the passage of direct rays from the lamp to the observer or to the instrument.

2. An instrument board, comprising a 80 main body having a sight opening therethrough, an instrument having a face to be read through said opening, means by which the instrument is held in place, a transparent cover carried by the main body 85 and covering the face of the instrument, an electric lamp arranged with its filament substantially in the plane of the transparent cover at an unobstructed edge thereof, and a shield preventing the passage of direct 90 rays from the lamp to the observer or to the instrument.

In witness whereof, I have hereunto set my hand at Indianapolis, Indiana, this 7th day of November, A. D. one thousand nine 95 hundred and nineteen.

CLARENCE E. JEFFERS.
